DOOR CLOSER

Frank M. Newell, Lowell, Mich., assignor to Newell Manufacturing Company, Lowell, Mich., a corporation of Michigan

Application July 15, 1957, Serial No. 46,948

Term of patent 14 years

(Cl. D10—7)

Fig. 1 is a side view of a door closer embodying my new design;

Fig. 2 is a fragmentary top plan view thereof; and

Fig. 3 is an end view.

The dominant features of the design reside in the portion shown in solid lines.

I claim:

The ornamental design for a door closer, as shown and described.
